UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed December 13, 1922. Serial No. 606,557.

This invention relates to internal combustion engines, and more particularly to ignition apparatus therefor. It contemplates the provision of a double ignition system, particularly for large, heavy duty airplane engines, which shall be reliable and efficient, which shall effect a material saving of weight in the engine as a whole, and which shall reduce the over all length thereof below that of previous units of corresponding power.

Another object of the invention is to so mount those units of the ignition system which require attention and adjustment, as to provide a maximum of accessibility thereto.

Other objects and structural features of this invention will appear from the subjoined description, taken in connection with the accompanying drawing, in which—

Fig. 1 is a side elevation, broken away and partially in section, of an internal combustion engine embodying the invention;

Fig. 2 is an end elevation of the engine shown in Fig. 1, viewed from the timing gear end;

Fig. 3 is a detail view, partially in section, of the magneto drive gearing;

Fig. 4 is a schematic view showing the exterior electrical connections to the magneto, and

Fig. 5 is a diagrammatic representation of the wiring of the magneto.

This invention has been illustrated and described in connection with an airplane engine of the V type but it is not to be understood as limited to power plants of this nature.

Among the principal desiderata of airplane power plants are reliability, and lightness in proportion to power. The first of these is absolutely essential, and in furtherance of this consideration many modern aircraft engines are equipped with double ignition. By a double ignition system is meant a system having duplicate sets of ignition apparatus, each complete in itself and each in itself sufficient to fire the engine. In this way the reliability of the apparatus is greatly increased, for if one of the sets should fail, the other would continue to supply the ignition for the engine. At the same time, by simultaneous operation of both sets, the flame propagation in the cylinders is increased, and the power of the engine thereby augmented.

These features have been obtained, however, at the expense of increased weight. In a double magneto system, for example, the duplication of the drive gearing alone adds very materially to the gross weight of the power plant. Many of the elements of a magneto are sufficiently sturdy to be practically indestructible, and failures rarely occur in the rotor, cam, shaft, bearings, magnets, or coupling, of one of these machines. On the other hand the windings, contact breakers, condensers, etc., are of necessity delicate, and should be duplicated to insure continuity of engine operation.

In view of these considerations, this invention provides a double ignition system for internal combustion engines in which the unnecessary duplication of parts is avoided, and the weight diminished while providing the maximum measure of reliability and accessibility.

With reference to the accompanying drawing an internal combustion engine is shown at 10, having two banks of inclined cylinders 11 and 12, arranged in the well known V form above a crank shaft 13. A housing 14 above each of the cylinder banks contains a longitudinally arranged cam shaft, mounted in suitable bearings and adapted to actuate rocker arms 16, which operate the engine valves against the action of springs 17 in the usual manner. Each cylinder bank is provided with a suitable intake manifold 18, to which fuel is supplied by a carburetor 19, and exhaust pipes 21, through which the engine exhaust is vented to the atmosphere. Each of the cylinders also contains the usual piston 22, connected by a rod 23 to a crank 24 of the engine crank shaft 13. The crank shaft 13 is journaled in bearings 26, 27, which has a removable lower portion or oil pan 28, forming an oil sump. One end of the crank shaft 13 is journaled in a suitable thrust bearing 29 beyond which it may be connected to an airplane propeller 31.

The other end of the crank shaft 13, beyond the end bearing 26, has a reduced portion 32, journaled in a bearing 33. Overhanging this bearing 33 at the end of shaft 13, is a bevel gear 34 rigidly secured to the shaft 13, in any appropriate manner. The bevel gear 34 drives a bevel gear 36 on a tubular shaft 37, vertically disposed below the crank shaft 13 and provided at its lower

end with a bevel gear 38 adapted to drive a suitable oil pump (not shown). Aligned with the shaft 37 and removably secured thereto is a shaft 39 adapted to drive a water pump 41, by means of which circulation in the engine cooling system is maintained.

Disposed above the crank shaft 13 is a vertical shaft 42, provided at its lower end with a bevel gear 43 adapted to mesh with 10 and be driven by the bevel gear 34. The shaft 42 is journaled at its lower end in a bearing 44, adapted to absorb thrust, and is provided, intermediate its ends, with a bevel gear 45, above which it is provided with a 15 guide bearing 46. The bevel gear 45 meshes with two bevel gears 47, attached to the inclined shafts 48, each of which drives one of the engine cam shafts through appropriate gears at its upper end (not shown). 20 The upper end of the shaft 42, is connected to the driving member of a coupling 49, adapted to drive the shaft 51 of a vertically disposed magneto 52.

The magneto 52 is enclosed in a dust and 25 water tight casing 53 and is provided with a cap 54 secured to the casing 53 by bolts 56, which pass through hollow lugs 57 on the casing 53 and secure the whole assembly to a bracket 58, formed on the engine base 30 between the cylinder banks. The magneto 52 is preferably of the well known inductor type, which lends itself readily to compact and light design, but any other type of magneto, such as the revolving armature 35 type, may be employed. The magneto contains the usual primary windings 61 and secondary windings 62, with contact breakers 63 in the primary circuit, shunted by condensers 64. These elements are arranged 40 in duplicate, one set for each branch of the double ignition system as shown in Fig. 5. The primary circuits are also connected to a suitable switch 65, by which either or both 45 of the branches of the system may be switched off or on. The terminal 66 of each of the two secondary windings 62 is connected by a cable 67 with the collector terminal of a rotary distributor 68.

The distributors 68 are of the well known 50 type having a central rotary shaft provided with a distributing arm 69, adapted to operate over a circularly arranged series of contacts, one for each of the engine cylinders. Each of these contacts is connected by a cable 71 to a spark plug 72 in the engine cylinder which it represents. There are two of the distributors 68, which are preferably mounted, as shown, on the ends of the housings 14, and driven from the engine cam 55 shafts, but it is to be understood that they may be mounted in any convenient place, as above the magneto cap 54, and may be driven in any suitable manner, as from the magneto shaft.

65 It will be observed that each of the engine

cylinders is provided with two spark plugs 72, and that each of the distributors 68 is connected by the cable 71 to one spark plug in each cylinder. Accordingly, each of the branches of the ignition system is in itself 70 complete and can supply to a spark plug in each cylinder the electrical impulses necessary to fire the engine.

The magneto 52, while generating the electrical energy for both of the branches of the 75 system, contains but a single housing, a single rotor and shaft, a single set of bearings, and a single cam. It will be understood that the cam operates both sets of contact breakers. Furthermore, only a single 80 drive shaft 42, a single set of driving gears 34 and 43, and a single coupling 49 is required, thus further materially reducing the weight.

By mounting the magneto 52 vertically in 85 the V of the engine, near the end thereof, its accessibility is much increased, and in addition it can be readily removed by unscrewing the bolts 56 and withdrawing them from the lugs 57, the shaft connection being broken 90 at the coupling.

It will be understood that various forms of the invention other than those described above may be used without departing from the spirit or scope of the invention. 95

What is claimed is:

1. In combination with an internal combustion engine having two banks of cylinders arranged in a V and provided with a double ignition system, a vertically disposed 100 shaft, a magneto arranged between the cylinder banks adjacent one end thereof and adapted to supply both branches of the double ignition system, and means connecting said magneto in driving relation with said 105 vertical shaft.

2. In an internal combustion engine having a double ignition system, a magneto disposed in the vertical plane of the engine crankshaft and adapted to supply both 110 branches of the ignition system, and means comprising a vertical shaft aligned with and adapted to drive said magneto from the engine crankshaft.

3. In combination with an internal combustion engine having a double ignition system, a magneto adapted to supply both 115 branches of said system, comprising a rotor, a contact breaker for each branch and windings for each branch, a shaft disposed vertically with respect to the engine crankshaft and means coupling said magneto to said shaft in driving relation.

4. In combination with an internal combustion engine having a double ignition system, a magneto adapted to generate electrical impulses to supply both branches of 120 said system, a magneto shaft connected to the engine, and separate distributing means for each of said branches, separately 125 connected to the magneto shaft.

65 It will be observed that each of the engine

nected to and driven from the magneto shaft.

5. In an internal combustion engine having a double ignition system, a magneto adapted to supply both branches of said system comprising a rotor, a shaft operatively mounted to drive said rotor, and a pair of distributors each adapted to supply one of the branches of the system, mounted independently of said shaft.

6. In an internal combustion engine having a double ignition system, a magneto having a single rotor to supply both branches of said system, a shaft adapted to drive said rotor from the engine, independent distributors for each branch of the system, and a separate driving connection from the said magneto shaft to each of the distributors connected to the magneto shaft between the engine and the rotor.

7. In combination with an internal combustion engine of the V type having overhead camshafts for each bank of cylinders, a magneto arranged in the V, having a vertical shaft and a rotor thereon, two contact breakers each adapted to operate one branch of a double ignition system, and a distributor for each branch mounted one on each camshaft.

8. In combination with an internal combustion engine of the V type, a vertical shaft in said V, means driving said shaft from the engine crankshaft, a camshaft for each bank of said engine, means driving each camshaft from the vertical shaft, a double ignition system for the engine, and a single magneto for said system having a shaft aligned with and coupled to the vertical shaft.

9. In combination with an internal com-

bustion engine of the V type having a double ignition system, a vertical shaft driven from the engine, a pair of inclined shafts adapted to drive the engine camshafts and driven from said vertical shaft, and a magneto vertically arranged between the cylinder banks of the engine and driven from the said vertical shaft, adapted to supply both branches of said double ignition system.

10. In an internal combustion engine having two banks of cylinders arranged in a V, a camshaft for each bank, an inclined shaft driving each camshaft, a vertically arranged shaft driving the inclined shafts and driven from the engine, a double ignition system for the engine comprising a magneto removably supported in the V and driven from the vertical shaft, adapted to supply electrical impulses for both branches of the ignition system, and distributing means for each of said branches mounted on and driven by the said camshafts.

11. The combination with an internal combustion engine having a crank case and banks of cylinders thereon inclined to form a V, of a cam shaft for each bank of cylinders, inclined shafts adapted to drive said cam shafts, a vertical shaft operatively connected to the engine and the inclined shafts, and a double ignition system for the engine including a single magneto secured to the crank case in the V and driven from the vertical shaft at the upper end thereof, said magneto being adapted to supply both branches of said system.

In testimony whereof I affix my signature.

LIONEL M. WOOLSON.
